UNITED STATES PATENT OFFICE.

FRANCIS E. STEVENSON, OF MOUNT GILEAD, OHIO, ASSIGNOR TO THE HYDRAULIC PRESS MANUFACTURING COMPANY, OF MOUNT GILEAD, OHIO.

REGULATOR FOR HYDRAULIC STEAM-PUMPS.

1,111,505.

Specification of Letters Patent.

Patented Sept. 22, 1914.

Application filed January 23, 1914. Serial No. 813,904.

To all whom it may concern:

Be it known that I, FRANCIS E. STEVENSON, a citizen of the United States, residing at Mount Gilead, in the county of Morrow 5 and State of Ohio, have invented certain new and useful Improvements in Regulators for Hydraulic Steam-Pumps, of which the following is a specification.

The object of this invention is to provide 10 a simple compact and automatic means for controlling hydraulic steam pumps and especially pumps of this class which operate intermittently. According to my invention I provide a governor or regulator which 15 cuts off the steam supply to the pump when a predetermined maximum pressure is reached thereby effectually preventing damage to the pump, presses, press fittings, etc., which would result from excessive pressure, 20 and which regulates the speed of the pump to any number of strokes for which it may be adjusted, thus preventing damage from racing if the pressure should suddenly be released.

25 In carrying out my invention I provide a governor or regulator having a valve chamber formed with steam inlet and outlet ports controlled by two hollow piston valves in line with each other within said chamber.

30 One of these valves controlling the steam admission port is attached to a piston rod which extends into a hydraulic pressure chamber connected with the hydraulic pump to be regulated. This piston rod is provided 35 with devices for adjusting its length. The other piston valve, *i. e.*, that controlling the outlet from the valve chamber has a valve stem in line with the piston rod above referred to and its outer end extends through

40 a yoke on opposite sides of which are hand wheels adjustable on a threaded outer part of the stem. The outer opposite ends of the yoke are attached by adjustable nuts to rods which extend through arms projecting laterally from the piston rod and these rods carry 45 adjusting nuts on opposite sides of said arms so that the distance between the yoke on the valve-stem and the arms on the piston rod may be adjusted. The rods just referred to,

50 which I call strain rods, extend through arms of the regulator frame and are connected at their outer ends by a yoke or spring cap between which and the frame is interposed a spring which tends to hold the outlet valve of the valve chamber fully closed

and the inlet valve fully open. The outer ends of the strain rods are threaded and carry adjusting nuts which bear on the adjacent yoke or spring cap and by means of which the tension of the spring may be adjusted to determine the normal positions of the valves. By these devices the regulator may be adjusted to automatically control the admission of steam to the pump without the slightest attention on the part of the operator, the steam supply to the pump being automatically cut off when a predetermined maximum pressure is reached and the speed of the pump being regulated to any desired number of strokes as conditions may require. 60 65 70

Other features of my invention are hereinafter described.

In the accompanying drawings, Figure 1 shows a top plan view of my improved regulator. Fig. 2 shows a vertical central section thereof. Fig. 3 is a detail view showing how one of the strain rods is connected with other parts of the mechanism. 75

The regulator is applied to the hydraulic steam pump in the usual way and is connected with a suitable source for supplying steam. The valve casing A is provided with a steam inlet B and a steam outlet B' which latter leads to the steam chest of the steam pump in the usual way. 80 85

C indicates a frame applied to the valve casing and bolted thereto as indicated at c. Within the valve casing or in the valve chamber is a hollow piston valve D provided with ports d connected with a steam inlet port d', and E indicates a hollow piston valve within the valve chamber having ports e connected with the outlet port e' delivering to the outlet B' connected with the steam chest of the pump. 90 95

It will be observed that the valves are within the same valve chamber but are close together and are in line with each other, a small space x only being left between them. This is a compact arrangement and one that 100 is serviceable in practice.

The valve E is attached to a piston rod F which extends through suitable packing f in the valve casing and also through packing f' in the casing of the pressure chamber G. 105 Preferably the rod F is made in two parts and its length may be adjusted as hereafter described. The pressure chamber is connected to a pipe H which should lead to the discharge of the hydraulic pump or 110

- to the hydraulic pressure line. The casing of the pressure cylinder G is formed with arms g bolted at g' to the arms c' of the frame C and thus made rigid therewith.
- 5 The valve E has a stem I passing through suitable packing K and also passing freely through a yoke L. The valve stem is threaded as shown and carries on opposite sides of the yoke threaded hand wheels N, M, by means of which the normal position of the valve E within the valve casing may be adjusted. The outer opposite ends of the yoke L are connected with the strain rods O and P. The threaded ends of the rods O and P
- 10 pass freely through holes in the yoke and carry adjustable nuts o , p by means of which the position of the yoke L on the rods may be varied. These strain rods have enlarged portions o' which extend freely
- 15 through the opposite ends of a yoke Q which connects the two members y , y' of the rod F. The member y of the rod F is formed with a collar y^2 which bears against the yoke Q and the other member y' of the rod F carries an adjustable nut y^4 . The opening
- 20 through the yoke Q is threaded as shown and by means of the devices mentioned the length of the rod F may be suitably adjusted. The strain rods carry adjusting nuts q
- 25 on opposite sides of the yoke Q and the shoulders q' of the enlarged portions of the strain rods normally bear against the arms c' of the frame C and those portions of the rods beyond the shoulders extend freely
- 30 through openings in said arms c' , g and are connected at their outer ends by a yoke or spring cap R between which and the pressure chamber G is interposed a spring S. The threaded outer ends of the strain rods
- 35 extend freely through holes in the yoke or spring cap R and carry on their outer ends adjustable nuts r , r' . The pipe H extends freely through an opening r^2 in the yoke R. This construction is very compact and all
- 40 the forces required to move the valves are in line with the valves themselves thus avoiding all side strains, and no tools are required for adjusting the valves to accommodate different speeds.
- 45 It will be observed that there are two sets of ports controlled by two valves and that when the hydraulic pressure increases, the piston valves governing these ports are suitably changed. Each of the piston valves
- 50 may be adjusted independently of the other and when the adjustment is made for speed at low pressure there is no danger of disturbing the adjustment at the opposite end of the governor.
- 55 In this apparatus when the hydraulic pressure is low the valve D is fully open and if the valve E is adjusted for high speed, the valve E is also fully open. As the pressure increases the valve D is gradually
- 60 closed. If the speed of the pump increases

on account of decrease of pressure the valve E is gradually closed. When the piston F is moved by an increase or decrease in hydraulic pressure, a corresponding movement is always given to the valve D, and as said piston rod F is connected with the strain rods O and P as before described, such strain rods move correspondingly with said rod F and impart a corresponding movement to the valve E, at the same time, by the devices before described, the valves D and E may be independently adjusted. It will thus be understood that the governor entirely cuts off the steam supply to the pump when a predetermined pressure is reached and regulates the speed of the pump to any desired extent. When there is no pressure in the hydraulic system, the pressure-control valve D should stand with its ports fully open and this adjustment may be accomplished at the factory and need not be changed. The speed-control valve E should be adjusted while the pump is running with no pressure in the pressure cylinder G.

To increase the speed of the pump the hand wheels M and N should be loosened and the wheel M should be drawn up against the yoke L. To decrease the speed, the wheel M should be loosened and the wheel N should be drawn up against the yoke tightly. When the speed has been properly adjusted the pressure may be allowed to rise in the hydraulic pipe line. If the gage shows that the pressure is rising above that for which the equipment is designed, the steam throttle valve may be closed and the spring S should be loosened by slightly "backing off" the nuts r , r' . If the pressure does not rise high enough, more compression should be given to the spring S by screwing down the nuts r , r' , but without closing the steam valve. When once properly adjusted the apparatus will operate in the manner before described.

I claim as my invention:

1. A regulator for hydraulic steam pumps, comprising a valve chamber having inlet and outlet ports for steam, two independently adjustable piston valves therein controlling the inlet and outlet ports of the valve chamber and which are in line with each other, an adjustable spring connected with said valves for holding them in a predetermined position to obtain a definite pressure in the hydraulic apparatus with which the regulator is connected, a piston connected with the inlet valve and connected also with the hydraulic apparatus for moving said inlet valve to close the inlet opening to the valve chamber, and adjustable connections between said piston and the outlet valve.

2. A regulator for hydraulic steam pumps, comprising a valve chamber having inlet

and outlet ports for steam, two piston valves therein controlling the inlet and outlet ports of the valve chamber and which are in line with each other, a piston connected with 5 the steam inlet valve, a spring connected with said piston and tending to hold the valve open, a pressure chamber into which said piston extends and which is connected with the hydraulic apparatus to be regulated 10 and which receives fluid that causes the steam inlet valve to close when a predetermined pressure is reached, means for adjusting the length of said piston rod,

means for adjusting the tension of the spring, connections between said piston and 15 the steam outlet valve, and devices for adjusting the position of said outlet valve independently of the adjustment of the inlet valve and which operate in line with said piston. 20

In testimony whereof, I have hereunto subscribed my name.

FRANCIS E. STEVENSON.
